PARACHUTE CONTAINER OF FOLDED PAPER

Leonard P. Frieder, Great Neck, and Walter S. Finken, Brooklyn, N. Y., said Finken assignor to said Frieder

Application August 17, 1945, Serial No. 611,094

13 Claims. (Cl. 244—148)

1 This invention relates to packages and particularly to an aerial delivery release package including a container from which a parachute may be released. Among the objects of the invention is to provide a container or parachute-enclosing casing which may be made from light materials and easily assembled with a parachute and a static cord and which will contain the parachute and static cord in such a manner as to facilitate the withdrawal of the static cord without interference from the contents of the package, and provide for the ready release of the parachute from the container.

Another object of the invention is to provide a 15 parachute-containing package which will easily open and release the contents of the package at the proper time during use.

It is important that the casing or enveloping portion of a parachute package be relatively light and at the same time be sufficiently strong to withstand transportation and protect the contents in their original folded condition. The container of the present invention is particularly suited for containing a parachute by which pigeons can be landed. The container encloses a static cord which is tied to the package and is adapted to be anchored at one end when the package is thrown overboard from an aircraft. The package is provided with an opening for the protrusion or accessibility of the shrouds of an 20 enclosed parachute whereby a load may be attached to the shrouds or to connecting members attached to the shrouds. The package is so constituted as to immediately open and release the parachute when the fall of the package is arrested and the effect of the falling load is exerted on the package. A load constituting a cage containing pigeons can be released from the package without excessive jolting or injury to the pigeons. Any container attached to a static cord would be 25 abruptly arrested in its fall, but the package of the present invention is so designed that when the fall of the container is arrested the load will open the container and draw the parachute therefrom with a minimum amount of transference of shock to the pigeons constituting part of the load. The static line thereafter becomes effective to open the canopy of the parachute. While the enveloping material or casing of the package is made relatively light, and preferably from folded paper, it is so constituted as to retain its form and protect the enclosed parachute and at the same time afford means for quickly releasing the 30 parachute. The attainment of these results constitutes objects of the invention and other objects

will be set forth in the accompanying specification and claims and shown in the drawings.

The drawings illustrate the principle of our invention and the best mode in which we contemplate applying the same.

In the drawings:

Fig. 1 is a plan of a blank before folding into a container;

Fig. 2 is a section on line 2—2 of Fig. 1;

Fig. 3 shows an outside view of the container folded in tubular form, but without being laced along its longitudinal laps;

Fig. 4 is a view of the casing showing the manner in which the static cord is attached and contained;

Fig. 5 shows the closed container in tubular form ready for the insertion of the parachute;

Fig. 6 illustrates the manner in which the container is finally closed;

Fig. 7 is a section on line 7—7 of Fig. 3;

Fig. 8 is a section on line 8—8 of Fig. 6 and showing the folded parachute and lines as viewed from the opening end of the container;

Fig. 9 is a longitudinal section on line 9—9 of Fig. 6;

Fig. 10 illustrates the complete package;

Fig. 11 is a perspective view illustrating the manner in which the package of Fig. 10 is contained in a protective wrapper;

Fig. 12 is a carton for containing the wrapped package;

Fig. 13 illustrates an opened carton;

Fig. 14 illustrates the opened container and released parachute; and

Fig. 15 is a section on line 15—15 of Fig. 14.

The container or casing of the package has four double side walls running longitudinally of the package and two end walls for closing the ends of the package. The end walls are of a

40 single thickness and each end wall is provided with a pair of flaps which are tucked into the package when it is finally closed. The entire casing is formed from a single blank of paper and is die-cut. While the shape of the package

45 may vary, as desired, the blank of paper may be cut as illustrated in Fig. 1, making allowance, however, for turned-over edges which are sewed or otherwise fastened by adhesive to the portions of the blank which they contact. These turned-

50 over edges serve to stiffen the edges of the blank and are desirable, though not indispensable, when paper of relatively light weight is employed. A paper of the grade of manila paper has been found suitable. If heavier paper is employed, 55 the turned-over edges may be dispensed with.

Folded-over edges are shown at 10 and 11 at the ends of the blank, and interrupted folded-over edges are shown at 12, 13, 14, 15 and around the edges of the tabs 16, 17, 18 and 19.

The rectangular area 20 constitutes the inside wall of the back of the container. The outside wall of the back of the container is double-ply and consists of an area 21 of the blank and a panel 22 in the form of a sheet of paper which is attached to the blank by sewed seams 23 and 24. The blank is first folded along line A—A so as to superpose the area 20 over the area 21 and panel 22, thereby forming a shallow or flat compartment 25, Fig. 7, between panel 22 and area 20. The lines of fold of the blank are illustrated in Fig. 1 as dash lines and as dash-and-dot lines, the dash lines illustrating the folds which are made by folding the blank upwardly, and the dash-and-dot lines, the folds which are folded downwardly as the blank is viewed in Fig. 1.

The fold lines A—A and B—B are so located as to provide folded meeting edges centrally of the front of the casing. The blank is notched at 26, 27 to provide an opening 50 at one end of the package through which the shrouds extend, as shown in Figs. 3 and 10. Reference to the front, back, and left and right side walls of the box, as made herein, is purely for the purpose of orientation for simplifying the description of the manner in which the blank is folded.

With the blank folded on line A—A and the area 20 overlying panel 22, area 23 and area 29 will be located opposite each other to form the inside and outside walls at the left side of the package, and area 30 will be superposed on area 31 to form the inside and outside walls at the right side of the package. Superposed areas 32 and 33 will constitute the right half of the front wall of the package.

The right double wall is formed by folding along coinciding lines 34 and 35, and the right half of the top is formed by folding areas 32 and 33 along coinciding lines 36 and 37. The left wall is formed by folding superposed areas 28 and 29 along coinciding lines 38 and 39. The left half of the front of the casing is formed by folding areas 40 and 41 against each other with line B—B forming the connecting line of fold. The folded relationship of the walls thus far described is shown in Fig. 7. Outside of line 43 there is an area 44 which extends outwardly, as shown in Fig. 7, and constitutes with area 20 the outside layer of the double wall at the left side of the casing when these two areas are joined together. These areas are joined together by lacing, and preferably by a lacing formed by passing an intermediate portion of the static cord 45 through two series of grommets 46 and 47 distributed along the longitudinal edges of areas 29 and 44, respectively.

Before the areas 29 and 44 are joined to close the outer wall of the casing, the tubular form of the casing is completed by the use of a tearable or weakened strip 48, which is secured to the flaps formed by areas 40, 41 and areas 32, 33, as shown in Fig. 7. This weakened strip may be made of paper similar to the paper from which the blank is formed and is provided with a series of perforations 49 to provide a weakened line. The strip is so placed that the weakened line of perforations will lie intermediate the spaced edges of the flaps and extend their full length from the opening 50. Opening 50 provides for the extension of the shrouds of the parachute as will be explained hereinafter.

The strip 48 may be sewed or otherwise secured

to the flaps and it is preferable that the strip be placed interiorly of the flaps and sewed to the flaps adjacent their outer edges so that the stiffened, rounded edges of the flaps will provide suitable resistance against improper tearing of the package and direct the tearing through the line of perforations 49. The inserting and attaching of weakened strip 48 completes the formation of the main compartment in tubular form.

When the front wall of the package is closed by strip 48, the main compartment of the container is closed except at its ends, and the edge areas 29 and 44 of the blank remain to be engaged for joining the outer wall entirely around the smallest perimeter of the package. The tubular form of the main compartment is illustrated in Figs. 3 and 7. The static cord 45 is employed as a tying means for bringing together the two halves of the left outer side wall. While various methods of lacing the static cord through the grommets 46 and 47 of the respective portions of the side wall may be employed, we find it convenient to apply the static cord as illustrated in Figs. 4, 8, 10, 14 and 15. This is accomplished by forcing loops 51, 52, 53, 54 and 55 through individual pairs of grommets 46 and 47, except the upper pair, and then threading the cord outwardly through the upper of grommets 46 and outwardly through the upper of the grommets 47, as shown in Fig. 4. This portion of the static cord is then passed through the loops 55, 54, 53, 52 and 51, in the order named, and tightened when the flaps of the outer side wall are overlapped. This end of the static cord then passes on and is tied to the hem or hem cord 56 of the canopy 57, Figs. 5 and 14. 58 is a weakened section located in the static cord between the casing and the parachute and is usually so located as to be attached to the hem of the parachute. It is severed after the parachute has been released and the static cord has served its function in opening the parachute.

Before the lacing is completed, the intermediate portion of the static cord is folded in a series of groups of foldings which are supported by a pair of tapes 59, 60, which are fastened to the panel 22, Fig. 4. The tapes are fastened by a series of stitchings 61, 62, 63, 64, etc., as shown in Fig. 4, and groups of foldings of the static cord are inserted between stitchings. The static cord is so folded that it will readily pull out from between the series of nests which are formed by the tapes and the series of stitchings. The stowing of the static cord is accomplished before the outer wall 21, 22 is folded against the inner wall 20, with the result that the static cord is stowed in a substantially flat compartment which is open at its ends. The anchoring end 65 of the static cord extends from one end of the compartment, and the other end 66 is folded with the parachute and extends into the parachute compartment, as shown in Figs. 8 and 10. The parachute, in folded condition, is slid into the main compartment in such a manner that the shrouds 67 extend through opening 50, as shown in Fig. 10.

The end walls 69 and 70 are then folded on lines 71 and 71^a, respectively, and as this is done the webs 72, 73, 74 and 75 are folded so as to be covered by the end walls. The end walls 69 and 70 are held in package-closing position by tabs 16, 17 and 18, 19, which are tucked into the spaces between double walls 40, 41 and 32, 33. This manner of sheathing the tabs between inner and outer walls facilitates the introduction and withdrawal of the tabs without interference

by the parachute. The manner of closing the end walls and of inserting the tabs is illustrated in Figs. 6 and 9, Fig. 9, showing tab 16 retentively held between areas 32 and 33 of the top side wall. The complete package is illustrated in Fig. 10 with a short end of the static cord 45 and the shrouds 67 exposed.

The package as thus far described is complete and ready for use. However, before shipment from the factory, the package is enclosed in a moisture-proof foil 76, Fig. 11. Preferably, aluminum foil is employed for this purpose. The package is wrapped between two sheets of foil which are sealed at their edges 77 after air has been evacuated from the package. The sealed edges 78 are folded over, as shown at 79, and the vacuum-wrapped package is ready for insertion in a carton 80, Fig. 12. This carton has the usual overlapping flaps at one end and an opening cord 81 by which an edge 82 of the carton can be easily severed, as illustrated in Fig. 13, when access to the wrapped parachute package is desired.

For using, the package is taken from its container and the enveloping foil is removed. The load is attached to the loops 83 of the shrouds which extend from within the package. The end 65 of the static cord 45 is attached to an anchor on an aircraft. The operator supports the package and its load by grasping the package and the shrouds, or shroud button 84, with the load dangling from the shrouds. The package and load are thrown overboard and as they fall the static cord is withdrawn from the package, except for the portion which has been attached thereto. When the full length of the available loose cord has been withdrawn, the fall of the container is interrupted, with the result that the inertia of the load pulls on the shrouds and causes severing of the tearable strip of material 48 along its weakened line and the opening of the container. The end wall 70, which normally is held in place by the frictional engagement of the flaps 18 and 19 between the inner and outer front walls, gives way and the parachute is fully released from all restraint from the container simultaneously with the opening of the container along the line of tear. When the parachute is free, the static cord will cause the parachute to open and the pull of the parachute upon opening will break the static cord at its weakened section 58. While the package may be made in different sizes to accommodate parachutes of various designs for alighting loads of a variety of forms, for the purpose of the present disclosure we have selected a pigeon carrier 85 as representing a load attached to the parachute.

It is to be understood that changes and modifications in construction, form and relative arrangement of parts, which will now appear to those skilled in the art, may be made within the scope of the invention. Reference is, therefore, to be had to the appended claims for a definition of the limits of the invention.

What is claimed is:

1. A package comprising a container and a folded parachute therein, including a canopy with attached shrouds, said container having a line of scoring longitudinally of one of its walls with an opening through the container which is intersected by said line of scoring and providing for the passage of shrouds from the enclosed canopy whereby said wall may be opened along the scored line and the parachute released from the package by a pull on the exposed shrouds.

2. A package comprising a container and a folded parachute therein, including a canopy with attached shrouds, said container having a side wall with an opening adjacent one end of the container for the extension of said shrouds to the exterior of the container and a weakened line in said wall leading from said opening and extending longitudinally of said wall, and a releasable end wall at the end of said container adjacent the terminus of said weakened line which is remote from said opening.

3. A package comprising a container and a folded parachute therein, including a canopy with attached shrouds, said container having a line of scoring in one wall of the package and an opening intersected by said line of scoring and providing for the passage of shrouds from the enclosed canopy to the exterior of said container, and a static cord attached to said parachute and partially contained in said container with an intermediate portion thereof secured to said container, said partially contained portion of the cord being withdrawable from said container without disturbing the contained parachute, and the withdrawal of the parachute being attainable by the severance of said line of scoring by a pull on the exposed shrouds.

4. A package of the character described, including a folded parachute comprising a canopy with attached shrouds, said package providing a compartment for containing said folded canopy and shrouds and having an opening in a wall for the protrusion of the shrouds from the package and a weakened line in said wall extending from said opening, a static cord, a second compartment in said package separate from said first-named compartment for containing the major portion of said static cord and isolating the same from said parachute and having an opening at one of its ends for the passage of said static cord and means for attaching an intermediate portion of said static cord to a wall of said package.

5. A package of the character described, comprising a substantially rectangular container having a displaceable end wall retentively secured by said container and a side wall with a weakened portion and an opening, means on said container for fastening a suspension cord, and a folded parachute enclosed in said container and having means attached thereto and projecting through said opening whereby a load may be attached to the parachute without opening said container.

6. A package of the character described comprising a single blank of paper cut to provide four double side walls when folded and end-wall portions for forming end walls with flaps extending therefrom for tucking into the package, said blank having outer edges running longitudinally of the side walls and adapted for fastening together, means for fastening said longitudinally running outer edges, said package having one of its double side walls formed by two folded portions folded towards each other from

65 opposite directions and thereby providing separable, closely-adjacent, oppositely-facing, folded edges in said last-named double side wall for gaining access to the interior of said package, each of said folded portions comprising a paper portion folded back against itself with the fold line disposed to constitute one of the aforesaid separable, folded edges, releasable means securing said two folded portions together, said releasable means being connected to said two folded 70 portions along said separable folded edges and

bridging said edges at a plurality of localities longitudinally of said edges, and said releasable means thereby constituting a separable connecting structure in the side wall constituted by the aforesaid two folded portions, contents-means contained in said package and partially protruding from within said package and through an opening adjacent said releasable means, and means attached to said package for suspending said package whereby a pull on said contents-means against a pull on said suspending means will cause said releasable means to relieve the connection between said two folded portions of said last-named side wall and open said package.

7. A package of the character described comprising a container formed from a single blank of paper cut to provide four double side walls when folded, and portions for forming end walls with flaps extending therefrom for tucking into the container, said blank having outer edges running longitudinally of the side walls and adapted for fastening together in forming the container, means for fastening said longitudinally running outer edges, said package having one of its double side walls formed by two folded portions folded towards each other from opposite directions and fastened together by a weakened strip of material, said separable edges extending along and close to a single line running from one edge to an opposite edge of the aforesaid one of the side walls, each of said folded portions comprising a paper portion folded back against itself with the fold line disposed to constitute one of said separable edges, said separable edges thus comprising oppositely facing folds and said weakened strip being connected to both said folded portions along the aforesaid line of the separable edges, and contents in said container and including cords extending from within said container and through an opening at one end of said weakened material, and means attached to said container for suspending said container so as to enable said cords to be pulled to effect severing of said weakened material and the parting of the separable edges of said last-named side to release the contents of said container.

8. A package of the character described, comprising a container formed from a single blank of paper cut to provide four double side walls, when folded, and portions for forming end walls with flaps extending therefrom for tucking into the package, said blank, when folded, providing a main compartment enclosed by said four double side walls and by said end walls and having dimensions provided by said blank, the outer of said side walls of said compartment being formed from different portions of said blank having folded edges lying opposite each other whereby access may be obtained to the interior of said compartment upon separation of said folded edges, means attached to each of said folded edges of said last-named side wall for holding said side walls in contents-enclosing relationship, a folded parachute contained in said main compartment and having attached load-supporting means projecting out of the container at a locality adjacent the aforesaid holding means, said holding means being releasable by the load-supporting means when the pull of a load is exerted on the latter, whereby the folded edges may separate to release the parachute, a substantially shallow compartment between superposed layers of said blank which constitute one of the side walls of the package, said last-named compartment being open-

ended to enable the withdrawal of contained contents, a cord contained in said shallow compartment, said cord being attached at one end to the parachute and at an intermediate locality to the container and being adapted for attachment at its other end to constitute a static line, and means carried by end edges of the blank and engaging a portion of said cord whereby said last-named compartment is closed at said end edges of the blank.

10. A package of the character described comprising a single blank of paper cut to provide four double side walls when folded and portions for forming end walls with flaps extending therefrom for tucking into the package, said blank having edges running longitudinally of the side walls at both ends of the blank and adapted for fastening together in forming the package, said package having another side wall formed by two folded portions folded towards each other from opposite directions and fastened together by a strip of tearable material, a folded parachute in said package and including shrouds extending from within said package through an opening at one end of said tearable material, a static cord tied to said longitudinal edges and fastening them together and having one end attached to said parachute, and means disposed between the double walls of one side of the package for releasably holding an intermediate portion of said static cord within the package.

11. A package of the character described, comprising a single blank of paper cut to provide four double side walls when folded and portions for forming end walls with flaps extending therefrom for tucking into the package, said blank, when folded, providing a compartment enclosed by said four double side walls and by said end walls and having dimensions provided by said blank, one of said side walls being formed from different portions of said blank and providing folded edges lying opposite each other whereby access may be obtained to the contents of the package, means attached to each of said folded edges of said last-named side wall for holding said side walls in compartment-forming relationship, a folded parachute enclosed in said compartment and having a portion thereof extending outwardly of the package, a substantially flat and open-ended compartment between the walls at one side of said package, and means in said last-named compartment for supporting a static cord.

12. A package of the character described, comprising a blank of sheet material composed of a plurality of hinged sections which, when folded, define a compartment having double walls around its girth and end walls with tuck-in flaps, one of said double walls including an inner hinged section and outer hinged marginal sections of the blank superposed over said inner section, means for joining said marginal sections, said blank being folded to provide for parting another of said double side walls on a locus extending transversely the girth of the compartment and located intermediate said marginal sections, said locus being defined by folded edges of the hinged sections of said last-named double wall, said folded edges being disposed adjacent one another when said compartment is closed and separable from one another to part said last-named double wall to provide access to said compartment, the wall portions which are terminated by said folded edges being constituted by portions of sheet material which are respectively folded

back against themselves in opposite directions and which thereby provide oppositely facing, closely adjacent but separable folds extending along said locus and constituting said folded edges, and releasable means for normally closing said compartment by joining the sections of said last-named double wall across said locus, said releasable means extending along said locus and being connected to the separable, folded portions of the double wall on both sides of the locus.

12. A package comprising a container and a folded parachute therein, including a canopy having a hem and having line means attached to the hem of the canopy, said container having side wall structure with provision for said line means to extend out to the exterior of the container at the end of the side wall structure, said container having a releasable end closure and including structure separable by said line means upon pulling thereon for opening said container and for releasing said end closure, said separable structure including sheet material forming part of the side wall structure, said sheet material having weakened localities providing ready rupturing of the same along a line extending throughout the length of the side wall structure, whereby said sheet material may be opened along said line by pulling on the line means, said line means being connected to draw the parachute out of the package when the aforesaid separable structure is opened.

13. A package comprising a container having a displaceable end structure, side wall structure including a wall part having a weakened portion

extending lengthwise thereof, said container including structure providing an opening from the interior to the exterior at an end of the side wall structure, a suspension cord extending into the container, said container including means attaching an intermediate portion of said suspension cord thereto, a folded parachute enclosed in said container and having means attached thereto and projecting through said opening whereby a load may be attached to the parachute without opening said container, said parachute comprising a canopy having a hem, and said suspension cord being secured at its end to the hem of the canopy and having a weak portion intermediate its said end and its aforesaid attachment to the container.

Certificate of Correction

Patent No. 2,508,754

May 23, 1950

LEONARD P. FRIEDER ET AL.

It is hereby certified that errors appear in the printed specification of the above numbered patent requiring correction as follows:

Column 7, line 28, after the word "and" insert *thereby providing separable edges for gaining access to the interior of said container, said separable edges being;* and that the said Letters Patent should be read with these corrections therein that the same may conform to the record of the case in the Patent Office.

Signed and sealed this 5th day of September, A. D. 1950.

[SEAL]

THOMAS F. MURPHY,
Assistant Commissioner of Patents.
